US0D1075289S

(12) **United States Design Patent** (10) **Patent No.:** **US D1,075,289 S**
(45) **Date of Patent:** **** May 20, 2025**

(54) **FRONT POCKET ON BACKPACK**

(71) Applicant: **Dongguan Yingchen Electronic Technology Co., LTD**, Guangdong (CN)

(72) Inventor: **Xinhao Ai**, Shanghai (CN)

(73) Assignee: **Dongguan Yingchen Electronic Technology**, Dongguan (CN)

(**) Term: **15 Years**

(21) Appl. No.: **29/965,726**

(22) Filed: **Sep. 28, 2024**

(30) **Foreign Application Priority Data**

Jun. 17, 2024 (CN) 202430369594.8

(51) **LOC (15) Cl.** **03-01**

(57) **CLAIM**

The ornamental design for a front pocket on backpack as shown and described.

DESCRIPTION

FIG. 1 is a perspective view of a front pocket on backpack showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is a partial enlarged view of portion 9 in FIG. 1; FIG. 10 is a partial enlarged view of portion 10 in FIG. 2; and,

FIG. 11 is a perspective view of a front pocket on backpack showing my new design, in a closed state.

The broken lines depict environment of the front pocket on backpack and form no part of the claimed design.

The dash-dot-dash line is included for the purpose of illustrating the bounds of the enlarged view and forms no part of the claimed design.

1 Claim, 11 Drawing Sheets
